DOWNDRAFT CARBURETOR

Bert Beard, Detroit, Mich., assignor to George
M. Holley, Detroit, Mich.Application July 12, 1930. Serial No. 467,494
Renewed November 9, 1932

8 Claims. (Cl. 281—34)

This invention relates to a downdraft carburetor having a high speed fuel nozzle combined with an air vented compensating nozzle.

The specific object of this invention is to apply an accelerating pump to the air vented compensating nozzle, and a constant gravity head to the high speed fuel nozzle.

In the figures all the essential parts of the invention are arranged on one plane so as to simplify the description.

Fig. 1 shows the preferred construction.

Fig. 2 shows a modification of Fig. 1.

In the figures A is the float chamber containing the usual float mechanism which is no part of this invention, B is the pump cylinder located wholly within the float chamber, C is the guiding portion of a piston which consists of the parts C, D, E and F. D being the piston proper which comes in contact with the fuel.

This piston D is carried on C' which is an extension from C. A spring E separates the part C from D. The piston D is perforated, and the perforation is closed by an annular check valve F. This check valve F is carried on a step on the extension C'. The fuel entrance to the cylinder B is through the opening G located below the level in the float chamber A. The fuel outlet from the cylinder B is through the restricted orifice H, then through the perforated tube J to the annular nozzle K. In the center of the annular nozzle K an air passage M is provided for still further atomizing the fuel. In the bottom of the cylinder B a valve N is located, which is adapted to engage with the extension C'. When the piston descends this valve N is opened and so admits fuel to a passage O which discharges into the throat of a Venturi tube P, into the throat of which the annular nozzle K also discharges. It will be noted that the passage O discharges into P more than $\frac{1}{2}$ " below the level in the float chamber A. The venturi P discharges into the mixture outlet Q in which is located the throttle R. This throttle R is controlled by a lever S, which is manu-

ally controlled at one end and is connected at the other end through the rod T with the rod U. U engages with the upper side of the piston C so that when the throttle R is opened the piston C—D—E—F descends. The perforated tube J is vented to the air entrance through the passage V which communicates with an annular chamber W, which surrounds the perforated tube J. This being the well known Daimler construction as shown in the British 55 Daimler Patent No. 10,786 of the year 1885 page

2, line 28—31. An idling and low speed fuel arrangement Y—Z is of a well known type as shown connected to the annular chamber W through the restricted passage X, but as this is not part of this invention its specific details need not be described.

Fig. 2 shows a modification of the construction shown in Fig. 1 with the valve N located outside of the pump cylinder B and in the float chamber A. An arm V attached as a bracket to the arm U is arranged to engage with the upper end of the valve N when the throttle is opened wide.

Operation

When the engine is idling on the low speed passages X—Y—Z, the check valve F is in the position shown, that it is suspended on the step on the extension C', and fuel thus freely passes from A through G into the piston cylinder B, as the check valve F leaves the perforation in D open. When the throttle is opened the fuel in B acting on the check valve F raises it against the perforated piston D thus closing this perforation and trapping the fuel in the cylinder B, which therefore is forced through H into the perforated passage J. The fuel discharges from J into the annular passage K and so into the throat of the venturi P. Normally air enters about V and flows into the annular chamber W which surrounds J, and this air enters through the perforation and thus mingles with the fuel therein. When the throttle is open beyond half way that is to say at speeds corresponding to 55 miles per hour, C' the extension from the piston C engages with the valve N, then the fuel is forced up O as well as through J. This fuel discharges at O below the level in the float chamber A. Hence if the throttle is held wide open on a hill for example, and the engine speed drops so that practically no depression exists in the venturi P then fuel flows from A to B past the valve N up the passage O into the venturi P, and continues to flow under the influence of gravity head in the float chamber A. This feature is disclosed in the applicant's copending application Serial No. 422,516 filed January 22, 1930. The function of the spring E is to provide a "follow up" for the pump discharge so that when the throttle is snapped opened the pump continues to discharge. This well known feature is taken from the Munson Patent 1,228,692. As the outlet of O into P is below the fuel level in the float chamber there is no necessity to connect the passage O with the pump cylinder B, and if the valve N

is removed from the bottom of the cylinder B, as shown in Fig. 2, substantially equivalent results will be obtained. The valve N is then operated by an arm V attached to V so that the valve N opens at the same angular position of the throttle R as the valve N in Fig. 1 opens.

What I claim is:

1. In a carburetor having an air entrance, a mixture outlet, a throttle valve therein, a mixture chamber intermediate the throttle and the air entrance, a constant level fuel supply chamber, an accelerating pump fed therefrom, a piston in said pump, means interconnecting said piston with said throttle, an outlet from said pump discharging into said mixing chamber said outlet being vented to the atmosphere at a point above the level in said supply chamber, a second outlet from said pump discharging into said mixture chamber at a point below the level of said fuel supply, valve means engaging with said pump controlling said second fuel outlet whereby said second fuel outlet is only in operation when the throttle is substantially wide open.
2. In a carburetor having an air entrance, a mixture outlet, a throttle valve therein, a mixture chamber intermediate the throttle and the air entrance, a constant level fuel supply chamber, an accelerating pump fed therefrom, a piston in said pump, yieldable means interposed between said piston and said throttle, an outlet from said pump discharging into said mixing chamber said outlet being vented to the atmosphere at a point above the level in said supply chamber, a second outlet from said pump discharging into said mixture chamber at a point below the level of said fuel supply, valve means engaging with said pump controlling said second fuel outlet whereby said second fuel outlet is only in operation when the throttle is substantially wide open.
3. In a downdraft carburetor having an air entrance, a mixture outlet, a throttle valve therein, a mixture chamber intermediate the throttle and the air entrance, a constant level fuel supply chamber, an accelerating pump fed therefrom, a piston in said pump, means interconnecting said piston with said throttle, an outlet from said pump discharging into said mixing chamber said outlet being vented to the atmosphere at a point above the level in said supply chamber, another outlet from said fuel chamber discharging into said mixture chamber at a point below the level in said fuel chamber, valve means controlling said second outlet interconnected with said throttle so that said second fuel outlet is only in operation when the throttle is substantially wide open.
4. In a downdraft carburetor having an air entrance, a mixture outlet, a throttle valve therein, a mixture chamber intermediate the throttle and the air entrance, a constant level fuel supply chamber, an accelerating pump fed therefrom, a piston in said pump, yieldable means interposed between said piston and said throttle, an outlet from said pump discharging into said mixing chamber said outlet being vented to the atmosphere at a point above the level in said supply chamber, another outlet from said fuel chamber discharging into said mixture chamber at a point below the level in said fuel chamber, valve means engaging with said pump and controlling said outlet whereby said fuel outlet is held open when the throttle is substantially wide open.

discharging into said mixture chamber at a point below the level in said fuel chamber, valve means controlling said second outlet interconnected with said throttle so that said second fuel outlet is only in operation when the throttle is substantially wide open.

5. In a carburetor having an air entrance, a mixture outlet, a throttle valve therein, a mixture chamber intermediate the throttle and the air entrance, a constant level fuel supply chamber, an accelerating pump fed therefrom, a piston in said pump, means interconnecting said piston with said throttle, an outlet from said pump discharging into said mixing chamber said outlet being vented to the atmosphere at a point above the level in said supply chamber, an air vented well associated with said outlet, another outlet from said fuel chamber discharging into said mixture chamber at a point below the level in said fuel chamber, valve means controlling said second fuel outlet interconnected with said throttle so that said second fuel outlet is only in operation when the throttle is substantially wide open.

6. In a carburetor having an air entrance, a mixture outlet, a throttle valve therein, a mixture chamber intermediate the throttle and the air entrance, a constant level fuel supply chamber, an accelerating pump fed therefrom, a piston in said pump, yieldable means interposed between said piston and said throttle, an outlet from said pump discharging into said mixing chamber said outlet being vented to the atmosphere at a point above the level in said supply chamber, an air vented well associated with said outlet, another outlet from said fuel chamber discharging into said mixture chamber at a point below the level in said fuel chamber, valve means controlling said second fuel outlet interconnected with said throttle so that said second fuel outlet is only in operation when the throttle is substantially wide open.

7. In a carburetor having an air entrance, a mixture outlet, a throttle valve therein, a mixture chamber intermediate the throttle and the air entrance, a constant level fuel supply chamber, an accelerating pump fed therefrom, a piston in said pump, means inter-connecting said piston with said throttle, an outlet from said pump discharging into said mixture chamber at a point below the level of said fuel supply means, valve means engaging with said pump and controlling said outlet whereby said fuel outlet is held open when the throttle is substantially wide open.

8. In a carburetor having an air entrance, a mixture outlet, a throttle valve therein, a mixture chamber intermediate the throttle and the air entrance, a constant level fuel supply chamber, an accelerating pump fed therefrom, a piston in said pump, yieldable means interposed between said piston and said throttle, an outlet from said pump discharging into said mixture chamber at a point below the level of said fuel supply means, valve means engaging with said pump and controlling said outlet whereby said fuel outlet is held open when the throttle is substantially wide open.
